UNITED STATES PATENT OFFICE.

CLYDE N. RAYBURN, OF PITTSBURGH, PENNSYLVANIA, ASSIGNOR TO REYMER & BROTHERS, INC., OF PITTSBURGH, PENNSYLVANIA, A CORPORATION OF PENNSYLVANIA.

DESIGN FOR A BOX COVER.

Application filed November 21, 1928. Serial No. 28,958. Term of patent 14 years.

To all whom it may concern:

Be it known that I, CLYDE N. RAYBURN, a citizen of the United States, and residing at Pittsburgh, in the county of Allegheny and State of Pennsylvania, have invented a certain new, original, and ornamental Design for a Box Cover, of which the following is a specification, reference being had to the accompanying drawings, forming a part thereof, of which Figure 1 is a view of the top, Fig. 2 a view of the side, and Fig. 3 a view of the end of the box cover designed in accordance with this invention.

I claim:

The ornamental design for a box cover substantially as shown.

CLYDE N. RAYBURN.
